(57) **CLAIM**

The ornamental design for a proximal tibial prosthesis, as shown and described.

DESCRIPTION

FIG. 1 is a front perspective view of a proximal tibial prosthesis according to my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a bottom left perspective view thereof; and,

FIG. 9 is a rear perspective view thereof.

The broken lines of even length in the drawings illustrate portions of the proximal tibial prosthesis that form no part of the claimed design. The broken lines of uneven length are boundary lines that form no part of the claimed design.
